[57] **CLAIM**

The ornamental design for a transparent tool handle cover, as shown and described.

DESCRIPTION

FIG. 1 is a right side elevational view of a transparent tool handle cover according to the invention, the left side elevational view being an identical mirror image thereof, wherein the broken line showings of the tool head and shaft are for illustrative purposes only and form no part of the claimed design;

FIG. 2 is a front elevational view of the transparent tool handle cover, the rear elevational view being an identical mirror image thereof, wherein the broken line showings of the tool handle and shaft are for illustrative purposes only and form no part of the claimed design;

FIG. 3 is an enlarged sectional view taken along line 3—3 of FIG. 1; and,

FIG. 4 is a bottom plan view of the transparent tool handle cover.
